[57] CLAIM

The ornamental design for a flooring unit, as shown and described.

DESCRIPTION

FIG. 1 is a perspective view from above and to one side and one end of a flooring unit showing my new design; FIG. 2 is a perspective view from below and to the opposite side and end of the unit shown in FIG. 1; FIG. 3 is a sectional view on line 3—3 of FIG. 1; and, FIGS. 4 and 5 are views similar to FIGS. 1 and 2 showing a second embodiment of my new design.

FIG. 1

FIG. 3

FIG. 2

FIG. 5
